HEAD AND HANDLE FOR A TOOTHBRUSH

Per Lindbo, Oslo, Norway, assignor to A/S W. Jordan
Borste & Penselfabrik, Oslo, Norway

Filed July 29, 1971, Ser. No. 167,538

Claims priority, application Norway Feb. 5, 1971

Term of patent 14 years

Int. Cl. D4—02

U.S. Cl. D4—25

FIG. 1 is a side elevational view of a head and handle for a toothbrush,

FIG. 2 is a back elevational view,

FIG. 3 is a front elevational view,

FIG. 4 is a top plan view, and

FIG. 5 is a bottom plan view.

The broken line showing of the bristles in the several views is for illustrative purposes only and form no part of the claimed design.

I claim:

The ornamental design for a head and handle for a toothbrush, as shown and described.
